UNITED STATES PATENT OFFICE.

WILLIAM B. FARRAR, OF GREENSBOROUGH, NORTH CAROLINA.

TURBINE WATER-WHEEL.

SPECIFICATION forming part of Letters Patent No. 224,161, dated February 3, 1880.

Application filed November 8, 1879.

To all whom it may concern:

Be it known that I, WILLIAM B. FARRAR, of Greensborough, in the county of Guilford and State of North Carolina, have invented a new and Improved Turbine Water-Wheel; and I do hereby declare that the following is a full, clear, and exact description of the same.

My invention has for its object to provide an improved turbine water-wheel which shall be simple and inexpensive in construction, but strong, durable, and capable of running at comparatively high speed with moderate pressure, or comparatively low head of water.

In so far as my improved wheel resembles its predecessors it is a combination of the inward and downward flows, its main feature being the arrangement, within a casing and around a vertical revolving axis, of a series of diverging blades or buckets, which are placed at a downward inclination of forty-five degrees, or thereabout, and are made of gradually-increasing width from the upper to the lower end, and also have a spiral curve, to enable them to react on the water in the desired manner.

The invention also includes a casing having a conical top, in which are formed hoods or inlet-passages of peculiar construction, and closed by gates which are hinged near the apex of the case and operate vertically, as herein-after described.

In the accompanying drawings, forming part of this specification, Figure 1 is a side elevation of my improved water-wheel. Fig. 2 shows a vertical section of the wheel-case and a side view of the wheel proper. Fig. 3 shows cross-sections of the wheel proper on lines *xx* and *yy*, respectively, Fig. 2. Fig. 4 is a detail view of one of the wheel-blades or buckets detached and enlarged.

The case of the wheel consists, essentially, of the cylindrical portion or body *A* and the top, which has the general outline, or, rather, inclination, of a cone, but is composed of a series of hoods or water-inlet passages, *B*, whose construction will be more particularly described hereinafter.

The wheel proper consists of a vertical axis or shaft, *C*, and a series of blades or buckets, *D*, which have the following characteristics of form and local relation, to wit: They are long, thin, and narrow metal plates attached

to the shaft *C*, and diverging therefrom downward and outward at an angle of forty-five degrees, more or less, and are of gradually-increasing width, and also have a gentle spiral curvature from their upper to their lower ends, and they are straight on each side edge. Thus the body of the wheel is in the nature of a skeleton-cone having diverging ribs separated by slots of uniform, or nearly uniform, width from top to bottom.

In respect to certain other details, the construction, arrangement, and attachment of the buckets *D* are as follows: They are connected with an iron hub, *a*, in the process of casting, and said hub is suitably keyed on the shaft *C*, in the usual way. At their point of attachment to the hub *a* the buckets are narrow, and their diameter is nearly vertical, and from thence they are gradually widened and curved spirally, so that their lower ends are not only relatively broad, but their diameter at that point is at an angle of about five degrees to the plane of their diameter at the upper end. Said lower ends of the buckets *D* are rigidly connected by a circular band or rod, *b*, so that the body of the wheel has due strength, although of exceedingly light and comparatively slight construction.

The shaft *C* is stepped in a spider, *E*, and has its upper bearing in the top of case *A*, in the usual way. The water enters hoods *B* and rotates the wheel by acting on the buckets *D* as they successively pass beneath the openings in the hoods *B*. The conical construction of the wheel enables the weight of the impinging water to be fully utilized for rotary propulsion, or at least more fully than in other turbines in which the cone principle is not utilized, since the buckets are of the greatest length practicable, and are exposed to the action of the water throughout their length, yet the narrowness of the buckets enables the water to quickly discharge from or leave the wheel, so that there is no dead water carried by the latter. In my wheel, therefore, I combine with other desirable qualities adaptation for action of water on a comparatively large area or surface, with the greatest freedom of escape or quick delivery therefrom. Such free delivery has a very important effect in producing the high speed my wheel is capable of

attaining. The delivery is, however, at and over the ends of the buckets, as well as their inner or lengthwise edges.

The hoods B are formed by dividing the top 5 of the wheel-case radially, thus forming four sections, (there may be any other number,) and then elevating one edge of each quarter-section and applying a triangular piece, c, to the lower edge of each section. The hoods B 10 have thus a large triangular-shaped mouth, and their lower sides being at nearly a right angle to the top portion and inclined outward from the axis C, instead of being parallel, or approximately parallel, to it, so that the water 15 is admitted in largest quantity at the lower side of the mouth and converged upon the lower side of the wheel, where the capacity of the buckets and leverage of the wheel are greatest.

20 The mouths are closed or opened by gates F, which are of like triangular shape and pivoted at their upper ends to the wheel-case near the apex, so that their diameters are parallel to vertical planes, and when the gates 25 are closed their lower edges are parallel to the inclination of buckets D, as shown in Fig. 1.

When the gates F open, as shown in dotted lines, Fig. 1, the space formed thereby, 30 and through which the water enters, is triangular in shape, and hence the greater volume of water will always enter at the lower side of the mouths. In other words, the form of the hoods and their mouths and the form and 35 action of the gates have relation to the form and arrangement of the buckets, with a view to obtaining the greatest practicable propulsive effect from the smallest volume of water.

The gates are connected with a sliding collar, d, on the shaft C by means of rods G. The collar is raised by a pivoted lever, so that the gates are opened simultaneously. The said rods are made in two parts and connected by a tubular nut having a right and left screw-thread, so that the rods may be easily adjusted 45 in length to cause the gates to fit close on the case. A narrow flange, e, projects inward from

the upper part of the cylindrical portion or body of the wheel and covers the stay-band b of the wheel proper, thus serving to prevent 50 the water striking upon said band as it enters the passages B.

I do not claim, broadly, a wheel-case having an inclined top provided with hoods whose mouths are widest at the lower side and closed 55 by pivoted gates.

What I claim is—

1. A turbine water-wheel whose body is formed of a series of blades or buckets arranged divergently and at a downward inclination around a rotating shaft, to which their upper ends are attached, substantially as specified.

2. A turbine water-wheel having its body formed of buckets which are constructed of 60 thin metal blades of gradually increasing width from the upper to the lower end, and made straight on either edge, and arranged around the axis divergently but at a downward inclination of forty-five degrees, or thereabout, and also curved spirally lengthwise, 70 all as shown and described, to operate as and for the purpose specified.

3. In a turbine water-wheel, the combination, with the wheel-blades and the stay-band 75 b, attached to their lower ends, of the casing having the flange e, which projects inward over said band, as shown and described.

4. In a turbine water-wheel, the combination, with the conical wheel, of the conical 80 casing having hoods with triangular mouths, and whose lower sides are at right angles to the top portion, and also overhang the vertical side of the casing, and the triangular gates, which are pivoted at their upper ends, 85 so as to move in vertical radial planes in opening and closing, as shown and described.

The above specification of my invention signed by me this 5th day of November, 1879.

W. B. FARRAR.
